METHOD OF CLEANING CATCH BASINS

Ronald Clement Evans, Elgin, Ill., assignor to Municipal Appliance Company, New York, N. Y., a corporation of Maine

Application December 4, 1933, Serial No. 700,933

2 Claims. (Cl. 214—152)

This invention relates to a method of cleaning out catch basins, cess pools, grit containers, receptacles for collecting solid matter such as sludge from liquids and the like which involves the principle of an ejector jet for forcing the sediment from the basin to a settling tank. In order to maintain an effective jet, it is desirable that the jet producing mechanism be gradually lowered into the basin by a step by step movement and be maintained in the upper portion of the sediment which has been loosened or saturated by a disintegrating stream. It is further desirable to cause the sediment discharged into the tank to gravitate forwardly so as to increase the amount that can be deposited. To this end the sediment is maintained in a fluid state for a considerable time therein, as set forth in my co-pending application Serial No. 700,930, filed Dec. 4, 1933.

The invention comprises the novel method and steps hereinafter described and more particularly pointed out and defined in the appended claims.

In the accompanying drawings which illustrate a preferred apparatus for carrying out the method and in which similar reference characters refer to similar features in the different views:

Figure 1 is an elevational view of a part of the apparatus for carrying out my novel method.

Figure 2 is an enlarged fragmentary sectional view through the ejector mechanism.

Figure 3 is a fragmentary plan view of a portion of the apparatus.

Figure 4 is an enlarged fragmentary elevational view of a part of the apparatus illustrating the step by step mechanism.

Figure 5 is a longitudinal view thru a settling tank into which the sediment is deposited, and

Figure 6 is a sectional view upon the line VI—VI of Fig. 5.

The illustrated apparatus for carrying out the method will first be described. It comprises a pump 1 operated by a motor M to the outlet tube 2 of which there is connected a pipe section 3 having a valve controlled by a handle 4. From the outlet tube 2 there extends a valve controlled pipe 5 adapted to extend into the catch basin for disintegrating solid sediment and saturating the same. From the pipe section 3, there extends a pipe 6 for connection with a source of water supply for obtaining the initial water for the operation of the apparatus. A flexible pressure hose is connected to the pipe section 3 at one end while the other end is connected to a metal pipe 8 which is connected to the ejector nozzle hous-

ing 9 which is provided with an intake tube 10. Above the inlet of the pipe 8, there is a conical nozzle 11 with a restricted throat 12 whereby a vacuum producing jet is formed which draws the sediment thru the inlet tube 10. The nozzle housing 9 is connected to a discharge pipe 13 covered with a metal pipe 14 at its lower portion for protecting the same.

The sediment discharge pipe 13 is wound around a reel 15 and the upper end thereof is attached to a curved hollow arm 16 as indicated at 17. The hollow arm 16 communicates with the interior of the hub of the reel as shown in my co-pending application, Serial No. 700,930, filed Dec. 4, 1933. The hub of the reel communicates with a pipe 18 that discharges the sediment into a settling tank 19. The reeled portion of the conduit 13 constitutes a helical spiral path through which the educted material is impelled, and which path provides for a centrifugal movement of such material prior to its discharge into the tank.

The reel is provided with a sprocket wheel 20 around which a sprocket chain 21 is trained. The sprocket chain is also trained over a small sprocket 22 (Figs. 3 and 4) secured upon a shaft 23. An internal gear 24 is secured upon the shaft 23 and a pinion 25 is in mesh with the internal gear. This pinion 25 is secured upon a shaft 26 journalled in a suitable casting 28 and is provided at its outer end with a hand crank 27.

A ratchet wheel 29 is secured upon the shaft 26 and a pawl 30 pivoted to the casting normally engages the ratchet wheel. When the hand crank 27 is turned to elevate the hydraulic elevator, the ratchet wheel will be rotated in a clockwise direction and the pawl will ride idly thereover, but as soon as the hand crank is released, reverse rotation is prevented by the engagement of the pawl and ratchet. On the other hand, the pawl 30 may be disengaged and the hydraulic elevator allowed to descend by gravity as far as desired when the pawl may again be engaged with the ratchet to hold the elevator at the desired elevation. Thus the hydraulic elevator may be gradually lowered by a step by step movement so as to always extend the desired depth into the sediment in the catch basin.

The settling tank 19 embodies a pair of vertical plates 32 that extend from the rear to a point spaced a short distance from the front wall as shown in Fig. 5. These plates are also spaced from the side walls of the tank as shown in Fig. 6. The plates are secured to the top and bottom of the tank by means of angle clips 33.

The plates 32 are provided with drain apertures

34 which cover a substantially triangular area defined at its lower boundary by a diagonal plane extending from the upper rear corner of the tank. With this construction, the water in the sediment 5 cannot drain thru the plate 32 until it rises above the said diagonal plane. The water will therefore travel forwardly in the tank and carry some sediment therewith, until it drains thru the lower drain apertures. In other words the sediment is 10 maintained in a fluid state for a sufficient time to cause the same to flow toward the forward portion of the tank where it is arrested by a transverse drain plate 35 which is hinged to a rod 36 extending thru the sides of the tank. An angle 15 member 37 attached to the floor of the tank limits the forward movement of the tank.

The water which eventually drains from the sediment escapes from the tank thru a pipe 38 (Fig. 6) that communicates with a pipe 31 leading 20 to the pump 1, whereby the water may be again used.

The broad method involved in the above described apparatus consists in initially supplying the system with water disintegrating the contents 25 of the catch basin, creating an ejector jet in said contents for causing the contents to be discharged, maintaining the discharged sediment in a fluid state for causing the same to spread over a considerable area, then drawing the water 30 therefrom for re-use.

A more specific feature of the method resides in disintegrating the upper portion of the contents of the catch basin, creating an ejector jet in the disintegrating portion for causing the removal 35 thereof, then disintegrating a lower portion of said contents and lowering said ejector jet for causing the removal thereof.

It will be appreciated that according to the

present method it is possible to spread the discharged sediment over a wider area, and it is possible to control the depth of the ejector in accordance with the depth of the disintegrated material in the event that the contents of the catch 5 basin is of a considerable depth and solid or caked.

In the event it is not desired to use my novel tank and the steps involved in its use, then any other suitable tank may be substituted for the 10 tank disclosed herein.

I am aware that many changes may be made in the method and that certain steps may be varied without departing from the principles of this invention and I therefore do not propose limiting the patent granted thereon otherwise than necessitated by the appended claims.

I claim as my invention:

1. The method of cleaning out catch basins which consists in disintegrating the contents 20 thereof, creating an ejector jet therein for discharging the contents, maintaining the discharged contents in a fluid condition for a considerable height of deposit, draining said contents above a diagonal line to cause said deposits 25 to assume a sloping mass extending a considerable distance lengthwise and delivering said drainage back to said ejector jet.

2. The method of cleaning out catch basins which consists in disintegrating the contents 30 thereof, creating an ejector jet therein for discharging the contents into a tank, draining said discharged contents above a diagonal line to cause said material to gravitate in an inclined mass to substantially the front end of said tank 35 and delivering said drainage back to the ejector jet.

RONALD CLEMENT EVANS.
